UNITED STATES PATENT OFFICE.

JOHN L. SOMMER, OF NEWARK, NEW JERSEY, ASSIGNOR TO J. L. SOMMER MANUFACTURING CO., A CORPORATION OF NEW JERSEY.

GARMENT-HANGER.

1,282,480.

Specification of Letters Patent. Patented Oct. 22, 1918.

Application filed August 30, 1915. Serial No. 47,921.

To all whom it may concern:

Be it known that I, JOHN L. SOMMER, a citizen of the United States, and a resident of Newark, in the county of Essex and State 5 of New Jersey, have invented certain new and useful Improvements in Garment-Hangers, of which the following is a specification.

The objects of this invention are to provide an improved garment hanger for hanging up an entire suit or both coat and trousers; to provide a construction adapted to be readily manufactured from sheet material; to provide a hanger which will fold into a compact package; to obtain the proper curvature for the arms of the coat hanger and at the same time make the arms foldable; to form the coat hanger so that when folded it may carry the trousers hanger within itself; to secure simplicity of construction and 10 operation and to obtain other advantages 20 and results as may be brought out in the following description.

Referring to the accompanying drawings, in which like numerals of reference indicate 25 the same parts throughout the several views,

Figure 1 is a side elevation of a garment hanger embodying my invention, when folded;

Fig. 2 is a similar elevation showing one 30 arm of the coat hanger partially unfolded and the trousers hanger partially removed;

Fig. 3 is a side elevation of the coat hanger entirely open;

Fig. 4 is a perspective view of a portion 35 of one of the folding arms of the coat hanger;

Fig. 5 is a perspective view of the lower end of the arm supporting member of the coat hanger;

Fig. 6 is an elevation similar to Fig. 3, showing the opposite side thereof and the trousers hanger carried thereby in open condition;

Fig. 7 is a perspective view of one of the 45 trousers supporting arms;

Fig. 8 is a perspective view of the lower end of the supporting member for said arms;

Fig. 9 is a longitudinal section through 50 the folded coat hanger taken in a plane of the arms and showing the trousers hanger folded therein, and

Figs. 10, 11 and 12 are transverse cross-sections on lines A—A, B—B, and C—C respectively of Fig. 9.

55 In the specific embodiment of the inven-

tion illustrated in said drawings, the reference numeral 1 indicates a garment hanger made up of a coat hanger 2 and a trousers hanger 3. The coat hanger preferably comprises a sheet metal supporting member 4 60 adapted to extend laterally therefrom. Said supporting member is shown in the drawings as providing a hook 6 at its upper end and an elongated stem 7 in the plane of said hook and flaring adjacent its other end or bottom, 65 and the support being bent laterally from said bottom of the stem forming a transverse portion 8, see Fig. 5, and then bent back again parallel to and spaced from the stem and hook portion of the member as 70 at 9.

Between this parallel portion or lip 9 and the stem 7 are pivoted arms 5, 5, by suitable means such as the rivets 10, whereby the arms may swing flatwise of the stem 7 to 75 close or open the hanger. The pivotal mounting of the arms is such that as each is thrown into its open position the arm is stopped by and rests upon the edge of the transverse portion 8 of the stem 7 and preferably in such manner that said arms will both slope somewhat downward away from the pivotal mounting.

In order to fold the hanger with greater compactness, the arms 5, 5 are each made in 85 a pair of sections pivotally connected at their meeting ends by riveted pins 11 extending through both sections. Preferably the sections of each pair of arms are stamped up from sheet metal into channel shape, one 90 being of smaller cross-section than the other so as to fold or rest in it. Furthermore, the sections of each pair are assembled so that when thus closed one into the other their corresponding flanges and their webs are adjacent each folded arm being channel like, and the two arms are assembled so that they fold with their channel toward each other to form a pocket. For example, in the drawings the channel of the inner section, or section pivoted to the stem is large enough to receive the outer section within itself. Furthermore the channel of the inner section opens upwardly, with the arm extended, whereas the outer section, in extended position of the 105 arm, has its channel opening downward and it will therefore be obvious that when said sections are folded together they both will open outward in the same direction. Thus it is, when the sections are folded together 110

and the arms swung toward each other into folded position, as in Fig. 1, the channels are open toward each other providing said pocket thereby.

- 5 Preferably the arms 5, 5 are shaped to obtain the proper support for a garment, such as a coat, and for this purpose the sections of the arms are longitudinally concave or, with reference to their closed position, the 10 sections bow away from each other intermediate of their ends. Thus when the arms are extended, the inner section of each is curved with its center of curvature above the arm and the outer one with its center of curvature below the arm, forming, in other words, a reverse curve. By this means I obtain the 15 proper curvature for the arms of the hanger and at the same time permit the same to be folded compactly.
- 20 Stamped from the lower part of the stem 7 and from the transverse portion 8 is a strip of the sheet material bent into suitable shape to form a depending hook 12, adapted to carry the trousers hanger 3. Preferably 25 the hook is integral with the lip portion 9 of the supporting member so that its free end extends toward the stem. In hanging a coat upon the arms, the lip portion 9 of the hanger is positioned toward the back of the 30 coat and the stem toward the front which allows the coat collar to project forwardly as far as the stem and thus not be bent out of shape. Obviously with a coat applied to the hanger in this manner, the hook 12 is open 35 toward the front of the coat and the trousers hanger may be readily applied thereto or removed therefrom.

The trousers hanger comprises a supporting member 13 and a pair of arms 14, 14 40 pivoted thereto, said supporting member being flared adjacent its bottom so as to afford room for pivoting the arms adjacent each other flatwise of the supporting member. Furthermore, the supporting member is 45 preferably stamped from sheet metal and provides a hook 15 at its upper end with a depending stem. At the bottom of the flared end of this stem is a laterally bent portion 16, and the arms 14, 14 are pivoted to the stem 50 in such relation to said transverse portion as to engage the same when swung downward and be held thereby against swinging farther than into substantially perpendicular relation to the stem. To fold the hanger, 55 the arms are swung upwardly to lie adjacent to each other and to the supporting member.

60 Preferably, the arms 14 for the trousers hanger are stamped from resilient sheet metal, the same being each a narrow strip bent back upon itself intermediate its ends as at 17 and the two portions resiliently pressing toward each other to grip and support trousers or other garments inserted 65 therebetween. The pivoted end of the arm is

preferably longer than the free end and the free end bends at its extremity slightly away from the other portion of the arm so purchase may be obtained to insert the goods of the garment therebetween to force the two 70 portions of the arm apart and slide the garment between.

The length, thickness and width of the trousers hanger when folded are properly proportioned with respect to the coat hanger 75 to fit within the channel-shaped arms thereof and be included between the opposite pairs of sections when folded together. Furthermore, the arms of the trousers hanger are of such length that when carried between the arms of the coat hanger they underlie the riveted pins 11 thereof, see Fig. 9, and the trousers hanger will accordingly be prevented thereby from sliding longitudinally out. By arranging the trousers hanger 80 to fold within the coat hanger I obtain not only compactness, but also rigidity in that the trousers hanger prevents the coat hanger from being so readily bent while being carried and vice versa.

Having thus described the invention, what I claim is,—

1. A garment hanger comprising a coat hanger having channel-shaped arms each pivoted at one end and jointed intermediate 95 of its ends, each arm being thereby adapted to fold and the arms being also adapted to fold toward each other, and a trousers hanger adapted to be inclosed between said arms when folded toward each other.

2. A garment hanger comprising a coat hanger having a stem portion and channel-shaped arms each pivoted at one end to said stem portion and jointed intermediate of its ends, each arm being thereby adapted to 105 fold and the arms being also adapted to fold toward each other and provide a pocket therebetween, and a trousers hanger adapted to be folded and inclosed between the arms within said pocket.

3. A garment hanger comprising a coat hanger having channel-shaped arms each pivoted at one end and each composed of two parts foldable longitudinally of each other, a pin or the like extending through said 115 parts passing transversely through the channels thereof and hinging said parts together, said arms being also adapted to fold toward each other, and a trousers hanger adapted to be inclosed between said arms when folded toward each other and underlie said pins being held thereby against sliding longitudinally from between said members.

4. A garment hanger comprising a coat hanger having a supporting member with a 125 transverse portion from which extend a stem and a lip in spaced and parallel relation, channel shaped arms pivoted to said stem and lip to swing therebetween each arm having two parts, a pin or the like extending 130

through said parts passing transversely through the channels thereof and hinging said parts together, said arms being also adapted to fold toward each other, and a 5 trousers hanger adapted to be inclosed between said arms when folded toward each other and extending from the transverse portion of the supporting member to the said pins being held thereby against sliding 10 longitudinally from between said members.

5. A coat hanger comprising a support-

ing member and arms pivoted thereto, each arm being in sections pivoted together and said sections being of channel iron reversed in one with respect to the other so that when folded one nests within the other with their flanges projecting in the same direction and the arms when closed form between themselves a pocket to receive a trousers hanger or the like.

JOHN L. SOMMER.
